UNITED STATES PATENT OFFICE.

HALGE S. AXCELL, OF CHICAGO, ILLINOIS, ASSIGNOR TO W. A. SCHURMANN & COMPANY, OF CHICAGO, ILLINOIS, A CORPORATION OF ILLINOIS.

EGG-FILLER MACHINE.

1,198,512.

Specification of Letters Patent. Patented Sept. 19, 1916.

Application filed March 21, 1914. Serial No. 826,160.

To all whom it may concern:

Be it known that I, HALGE S. AXCELL, a citizen of the United States of America, and resident of Chicago, Cook county, Illinois, 5 have invented a certain new and useful Improvement in Egg-Filler Machines, of which the following is a specification.

My invention relates to filler machines of that kind in which two sheets are automatically fed and cut into strips having the formation necessary to enable them to be combined in the manner required to form a filler of the desired character. A filler of this kind, it will be understood, is employed, for 15 example, for holding eggs in place in a box or carton.

My invention relates more particularly to means for punching and feeding the two sheets of paper or other material, and is 20 in the nature of an improvement on the machine disclosed in my prior application No. 740,346, filed January 6, 1913.

Generally stated, the object of my invention is to provide a novel and efficient construction of the punching mechanism by which the two sheets are perforated before being fed to the means for severing or cutting them apart to form the strips.

A special object is to provide a novel and 30 improved construction and arrangement whereby only a single cross head is necessary, having punches at top and bottom thereof, the upper sheet being punched or perforated upon the upward stroke of said 35 cross head, and the lower sheet being perforated by the other set of punches upon the downward stroke thereof.

It is also an object to provide certain details and combinations tending to improve 40 the general efficiency and increase the reliability of a punching mechanism of this particular character.

To the foregoing and other useful ends my invention consists in matters hereinafter 45 set forth and claimed.

In the accompanying drawings—Figure 1 is a vertical section on line 1—1 in Fig. 2, showing a punching mechanism embodying the principles of my invention. Fig. 2 is a 50 vertical section on line 2—2 in Fig. 1. Fig. 3 is a vertical section on line 3—3 in Fig. 1. Fig. 4 is a perspective of one of the plates which hold the sheets of paper in place while being punched.

55 As thus illustrated, my invention com-

prises a body frame composed of two upright castings or frames A which are spaced apart and connected together by transverse or horizontal castings B and C, which are in the nature of stationary cross heads, whereby a rigid frame is provided for the various operative or moving elements of the machine. The vertically disposed rods D are arranged at opposite sides of the machine and slide up and down in guides b and c formed on the ends of the castings B and C, and have their lower ends connected to a cross head E, whereby the two rods move up and down in unison. The reciprocating cross-head E is actuated or reciprocated up and down by the pitmen e which have their lower ends connected to eccentrics e¹ on the shaft e², the latter being supported for rotation in suitable bearings on the body frame of the machine. The casting B is provided with openings b¹, and with a plate b² secured to the underside thereof by bolts or screws b³, said plate having smaller openings b⁴ which register with said other openings. The casting C is provided with openings c¹, and with a plate c² secured to the upper side thereof by bolts or screws c³, said plate having openings c⁴ which register with said other openings. A thin plate b⁵ is secured to the bottom of the plate b², with space b⁶ between them, this plate having a slot b⁷ which registers with the row of openings b⁴ in the other plate, (see Fig. 4). A similar plate c⁵ having a slot c⁶ registering with the openings c⁴ is secured on top of the plate c² with space c⁷ between them.

A crosshead F extends horizontally from one rod D to the other, being originally secured thereto in any suitable manner and disposed between the plates c⁵ and b⁵, said crosshead being formed with a space f extending through the middle or central portion thereof. The punches f¹ are arranged on top of said crosshead, being held in place by a plate f² secured by bolts or screws f³ to the upper surface of the crosshead. Each punch is disposed in a socket f⁴ in the plate f², and held therein by a wedge f⁵, or by any other suitable means. These punches f¹, when the crosshead moves upward, pass through the slot b⁷ and into the opening b⁴, whereby the sheet of paper X held in the space b⁶ is perforated in the desired manner. The lower punches f⁶, of suitable formation, depending upon the character of the 100

filler, are secured in a slot f^7 formed in the bottom of the crosshead F, and are held in place by set screws f^8 inserted horizontally in the crosshead. These punches f^6 , when 5 the crosshead moves downward, pass through the slot c^6 and into the openings c^4 , whereby the lower sheet of paper Y is perforated in the desired manner.

Any suitable means can be employed for 10 feeding the two sheets of paper. For example, the upper sheet X is pulled forward by feed rolls G disposed between the punching mechanism and the other elements of the machine, which latter are not shown, but 15 which it will be understood may be of any suitable or desired character. Feed rolls H are disposed in a similar position for the purpose of pulling the sheet Y through the punching mechanism. In this case, however, 20 the rolls H are provided with annular knives h which divide the sheet into parallel strips.

From the foregoing it will be seen that the upper sheet X is punched when the crosshead F moves upward, and that the 25 sheet Y is punched when the said crosshead moves downward. With this arrangement and mode of operation the punches are all carried on one and the same crosshead, the single crosshead being sufficient for both sets 30 of punches, and the two sheets of paper being alternately punched or perforated by the vertical reciprocation of said crosshead. The punches are all easily removed or replaced and are conveniently accessible for 35 this purpose. This construction and mode of operation, moreover, permits the machine to run at high speed.

It will be understood that any suitable means can be employed for rotating the 40 shaft e^2 , as well as for operating the feed rolls G and H, the feeding of the paper being properly timed or regulated with reference to the other elements of the machine in any suitable manner.

45. What I claim as my invention is:

1. In a carton machine, oppositely arranged stationary dies, means for feeding sheets between said dies, across the faces thereof, punches for said dies, disposed between said sheets, rigidly connected together, members for supporting and maintaining said punches in adjustment with said dies, and means for keeping said dies and punches in alinement and reciprocating 50 said members and thereby actuating the punches into and out of engagement with said dies to alternately perforate said sheets.

2. In a carton machine, oppositely arranged stationary dies, means for feeding sheets between said dies, across the faces thereof, punches for said dies, disposed between said sheets, rigidly connected together, and mechanism for keeping said dies and punches in alinement and reciprocating 55 said punches into and out of engagement

with said dies to alternately perforate said sheets, said dies being disposed one above the other, and means for supporting the upper sheet below the upper die.

3. In a carton machine, oppositely arranged stationary dies, means for feeding sheets between said dies, across the faces thereof, punches for said dies, disposed between said sheets, rigidly connected together, and mechanism for reciprocating said punches into and out of engagement with said dies, to alternately perforate said sheets, said mechanism including a pair of rods, a bar secured to and between said rods, operating means connected to said bar, thereby to 70 reciprocate said rods endwise and a cross-head upon which said punches are mounted, secured to and supported entirely by said rods.

4. In a carton machine, oppositely arranged stationary dies, means for feeding sheets between said dies, across the faces thereof, punches for said dies, disposed between said sheets, rigidly connected together, and mechanism for keeping said dies 75 and punches in alinement and reciprocating said punches into and out of engagement with said dies to alternately perforate said sheets, said feeding means being disposed in position to draw the perforated sheets from 80 said dies.

5. In a carton machine, oppositely arranged stationary dies, means for feeding sheets between said dies, across the faces thereof, punches for said dies, disposed between said sheets, rigidly connected together, members for supporting and maintaining said punches in adjustment with said dies, and means for reciprocating said members and thereby actuating the punches into and out of engagement with said dies, to alternately perforate said sheets, said machine having stationary cross heads, guides in said cross heads to govern the movements of said punches, and means to removably 100 secure the dies on said stationary cross heads.

6. In a carton machine, oppositely arranged stationary dies, means for feeding sheets between said dies, across the faces thereof, punches for said dies, disposed between said sheets, rigidly connected together, and mechanism for reciprocating said punches into and out of engagement with said dies, to alternately perforate said sheets, said dies being disposed one above the other, and means for supporting the upper sheet below the upper die, said machine having stationary cross heads, guides in said cross heads to govern the movements 115 of said punches, and means to removably secure the dies on said stationary cross heads.

7. In a carton machine, oppositely arranged stationary dies, means for feeding 120

- sheets between said dies, across the faces thereof, punches for said dies, disposed between said sheets, rigidly connected together, and mechanism for reciprocating said punches into and out of engagement with said dies, to alternately perforate said sheets, said mechanism including a pair of rods, a bar secured to and between said rods, operating means connected to said bar, thereby to reciprocate said rods endwise, and a cross head upon which said punches are mounted, secured to and supported entirely by said rods, said machine having stationary cross heads, guides in said cross heads to govern the movements of said punches, and means to removably secure the dies on said stationary cross heads.
8. In a carton machine, oppositely arranged stationary dies, means for feeding sheets between said dies, across the faces thereof, punches for said dies, disposed between said sheets, rigidly connected together, and mechanism for reciprocating said punches into and out of engagement with said dies, to alternately perforate said sheets, said feeding means being disposed in position to draw the perforated sheets from said dies, said machine having stationary cross heads, guides in said cross heads to govern the movements of said punches, and means to removably secure the dies on said stationary cross heads.
9. In a carton machine, oppositely arranged stationary dies, means for feeding sheets between said dies, across the faces thereof, punches for said dies, disposed between said sheets, rigidly connected together, members for supporting and maintaining said punches in adjustment with said dies, and means for reciprocating said members and thereby actuating the punches into and out of engagement with said dies, to alternately perforate said sheets, said machine including a pair of frames, members to rigidly connect said frames and support said dies, said members having guides for controlling the punches, said guides being disposed between said frames, and said members having openings for said dies.
10. In a carton machine, oppositely arranged stationary dies, means for feeding sheets between said dies, across the faces thereof, punches for said dies, disposed between said sheets, rigidly connected together, and mechanism for reciprocating
- said punches into and out of engagement with said dies, to alternately perforate said sheets, said dies being disposed one above the other, and means for supporting the upper sheet below the upper die, said machine including a pair of frames, members to rigidly connect said frames and support said dies, said members having guides for controlling the punches, said guides being disposed between said frames, and said members having openings for said dies.
11. In a carton machine, oppositely arranged stationary dies, means for feeding sheets between said dies, across the faces thereof, punches for said dies, disposed between said sheets, rigidly connected together, and mechanism for reciprocating said punches into and out of engagement with said dies, to alternately perforate said sheets, said mechanism including a pair of rods, a bar secured to and between said rods, operating means connected to said bar, thereby to reciprocate said rods endwise, and a cross head upon which said punches are mounted, secured to and supported entirely by said rods, said machine including a pair of frames, members to rigidly connect said frames and support said dies, said members having guides for controlling the punches, said guides being disposed between said frames, and said members having openings for said dies.
12. In a carton machine, oppositely arranged stationary dies, means for feeding sheets between said dies, across the faces thereof, punches for said dies, disposed between said sheets, rigidly connected together, and mechanism for reciprocating said punches into and out of engagement with said dies, to alternately perforate said sheets, said feeding means being disposed in position to draw the perforated sheets from said dies, said machine including a pair of frames, members to rigidly connect said frames and support said dies, said members having guides for controlling the punches, said guides being disposed between said frames, and said members having openings for said dies.

Signed by me at Chicago, Illinois, this 4th day of March, 1914.
